UNITED STATES PATENT OFFICE.

EDWARD W. KELLOGG, OF SCHENECTADY, NEW YORK, ASSIGNOR TO GENERAL ELECTRIC COMPANY, A CORPORATION OF NEW YORK.

RADIO RECEIVING SYSTEM.

Application filed October 29, 1924. Serial No. 746,648.

My present invention relates to radio receiving systems and more particularly to an arrangement of antennae which is especially adapted for radio reception. My present application is a continuation in part of my copending application, Serial No. 552,868, filed April 15, 1922.

In my U. S. Patent, 1,487,339 issued March 18, 1924, I have described and claimed a unidirectional antennae system made up of two horizontal conductors and have described and claimed a means whereby the antenna conductors may be employed as a transmission line for carrying signaling currents from a point in the antennae where they are most favorable for reception to a distant point along the length of the antennae where the receiving station may be more conveniently located. I have also described and claimed in that patent certain methods for neutralizing the effect of undesired currents in the receiving apparatus.

The object of my present invention is to provide a receiving system whereby the results described in my prior patent may be brought about in a somewhat simpler manner.

The improvements which I wish to cover in the present application consists principally in apparatus and connections for producing reflections of current, over the conductors of the receiving antenna in such a way that in some cases the need for current transformers may be eliminated. I have also provided simple means for adjusting the reflections in order to secure the most satisfactory reception.

The novel features which I believe to be characteristic of my invention are set forth with particularity in the appended claims, My invention itself, however, both as to its organization and method of operation will best be understood by reference to the following description taken in connection with the accompanying drawing in which Figs. 1 and 3 show diagrammatically three different circuit organizations whereby my invention may be carried into effect.

In each figure of the drawing I have indicated a long antenna made up of two parallel, horizontal conductors 1 and 2, ground connections are provided at the ends 3 and 4 of the antenna. In Fig. 1 the ground connection at 3 is made through a resistance 5 having a resistance substantially equal to the

surge impedance of the antenna to prevent undesired reflections back over the length of the conductors. In the arrangement shown in Fig. 1 it is assumed that it is desired to receive signaling waves traveling along the antenna through the ether from the end 3 toward the end 4 but that it is desired to locate the receiver 6 at or near the end 3 of the antennae. In order to be able to locate the receiving station at the end 3 of the antennae in this case it is necessary to provide means for transmitting the desired signaling currents received upon the antennae which are strongest at the end 4 back toward the end 3. In my prior patent above referred to I have accomplished this by means of a transformer located at the end 4. In the present case, however, the desired effect may be obtained by open circuiting the end of conductor 1 at end 4 of the antenna and directly grounding conductor 2. The result of this arrangement is to produce an open circuit reflection back along the length of conductor 1 which is superimposed upon the current wave built up on the antenna by the signal in such phase and magnitude as to produce zero current at the end 4 of conductor 1. At the same time a short circuit reflection is produced in conductor 2 which in effect practically doubles the current flowing in that conductor. Thus the opening of conductor 1 and the grounding of conductor 2 produces an effect at the end 4 of the antenna exactly equivalent to the effect obtained by the use of a transformer as described in my prior patent and the effect upon the receiver 6 will also be the same as though a transformer had been employed at the end 4.

The winding 7 of transformer 8 in Fig. 1 is not affected by currents flowing in the same direction in the two conductors of the antenna, but is affected by currents which flow in opposite directions in the two conductors. The signal waves built up on the antennae flow in the same direction through both conductors, but the waves reflected from the end 4 in the manner described in my present invention, flow in opposite directions in conductors 1 and 2 and therefore affect the receiving set 6 through the transformer 8.

By reason of the resistance in the ground connection at 4 there may be a loss of energy in the short circuit reflection and the re-

lected current in conductor 2 will then be less than that in conductor 1. This unbalance may in some cases be detrimental as will be more fully described later. This difficulty may be overcome by the provision of a leak resistance 9 which may be connected between the end of conductor 1 and ground by means of a switch 10. The resistance of this leak should be approximately such that $R_L:Z:Z:R_g$ in which proportion R_L is the resistance of the leak 10, R_g the resistance of the ground and Z the surge impedance of one conductor with ground return.

In my prior patent referred to above I have also indicated ways in which a portion of the currents which would flow through the ground connection at end 3 of the antenna, in the case just described, may be utilized for neutralizing the effects of disturbing currents which are found at the opposite end of the antenna and are transformed and transmitted over the line back to the receiver. In practice it is generally found desirable to make use of a neutralization of the nature described in my patent referred to and when such a system is employed the detrimental effects of an unbalance such as that referred to in the previous paragraph become more apparent.

In Fig. 2 I have indicated diagrammatically a receiving system in which means for securing such neutralization is provided. This system is so arranged that the currents in circuits 11 and 12 can be combined in any desired relative intensities and phases and supplied to the receiver 6. Assume that the desired signal is traveling in the direction 3—4 and that some disturbance which, for convenience may be called static, is coming from the opposite direction. The current indicated by the arrow marked I^a which is transmitted back to end 3 by means of the transformer is principally signal current with a residual of static while the current I^b is principally static. A small fraction of the energy of I^b is supplied to the receiver through circuit 12 in such phase and intensity as to balance out the residual static in I^a .

If now the transformer 13 is imperfect and instead of transforming all of the power brought to it by I^a reflects part of the waves back over the two wires in multiple the reflected component will then appear at 3 mixed with I^b . In attempting to make a balance for minimum static it now becomes necessary to use a mixture of I^a and I^b to balance the residual static in I^a and when the static is balanced it may frequently happen that the I^a component in circuit 12 has subtracted in the receiver from the I^a brought in through circuit 11 thus weakening the useful signal. Consequently it has been found in practice that the best balances are obtained when one of the components

has as much signal and as little static as possible and the other as much static and as little signal as possible.

Reflection at either 3 or 4 in this case tends to mix the two components before they reach the receiver where they are available for balancing operations. If the useful signal comes from the direction 4—3 and the static or interference from the direction 3—4 it is especially important to avoid reflecting part of I^a back over the two wires in multiple. This is because it does more harm to mix unnecessary static with signal current before the balancing operation, than to mix some signal current with the static. When a reflection transformer 13 is used as indicated in Fig. 2 it is desirable to use series and shunt resistances 14 and 15 on the primary side as shown in order that the total impedance in the ground connection may be more nearly a pure resistance and may be made more nearly equal to the surge impedance of the antenna. This throws away part of the static current I^a but there is a large surplus, since only a small fraction of I^a is required for balancing purposes. With the resistances 14 and 15 omitted it is difficult, because of the reactance of the transformer 13, to avoid reflecting a considerable fraction of I^a back over the antenna wires in multiple and having it appear mixed with the signal current I^b .

In Fig. 3 I have indicated a method whereby the result described in connection with Fig. 2 may be obtained without the use of the reflection transformer 13.

If the impedance or resistance of 16 is high compared with the surge impedance of one wire and that of 17 is correspondingly low the reflected waves on the two wires will be opposite in phase. If 16 and 17 differ only slightly from the surge impedance the amount of energy sent back on the transmission line will be small, most of the energy which reaches 4 being absorbed in the resistances. On the other hand if it is desired to transmit as much power as possible back over the transmission line, 17 should be zero and 16 should be an infinite resistance or open circuit.

If the waves built up on the antenna conductors are reflected at the end 4 the reflected waves may in any case be resolved into two parts, one consisting of a pair of waves identical in phase and magnitude on the two conductors and the other consisting of a pair of equal and opposite waves on the two conductors. The former represent power reflected back over the antenna which will appear in circuit 12 while the latter may be thought of as transformed waves. If we wish to avoid reflecting any of the power back over the antennae, the reflections on the wires individually must be equal and opposite. This condition may be met with

various combinations of impedances 16 and 17 some of which will absorb little power and transform most of it while others will absorb most of the power and transform 5 little.

What I claim as new and desire to secure by Letters Patent of the United States, is:—

1. The combination in a radio receiving 10 system of a long horizontal antenna made up of two parallel conductors, means at one end of said antenna for producing reflections of different phases in the two conductors and means for adjusting the reflections in 15 one of said conductors.

2. The combination in a radio receiving 20 system of a long horizontal antenna made up of two parallel conductors, means at one end of said antenna for producing reflections of different phases in the two conductors and means for adjusting the reflections in 25 both of said conductors.

3. The combination in a radio receiving 30 system of a long horizontal antenna made up of two parallel conductors, both of said conductors being grounded at one end and both of said conductors being grounded at another point through individual resistances of different values.

4. The combination in a radio receiving system of a long horizontal antenna made

up of two parallel conductors, receiving apparatus located at one point along said antenna, means at another point in said antenna for producing reflections of different phase in the two conductors and means for adjusting the reflections in one of said conductors.

5. The combination in a radio receiving 40 system of a long horizontal antenna made up of two parallel conductors, receiving apparatus located at one point along said antenna, means at another point in said antenna for producing reflections of different phase in the two conductors and means 45 for adjusting the reflections in both of said conductors.

6. The combination in a radio receiving 50 system of a long horizontal antenna made up of two parallel conductors, receiving apparatus located at one point along said antenna, means at another point in said antenna for transmitting energy over the two conductors to the receiving apparatus comprising means for producing reflections of different phase 55 in the two conductors and means for adjusting the amount of energy reflected and the phase of the reflections in the two conductors.

In witness whereof, I have hereunto set 60 my hand this 28th day of October, 1924.

EDWARD W. KELLOGG.
